By his Attorneys,

Inventor:
Francis E. Coffeen,

C. A. Snow & Co.

UNITED STATES PATENT OFFICE.

FRANCIS EDWIN COFFEEN, OF KANOPOLIS, KANSAS.

TIGHTENER FOR FENCES.

SPECIFICATION forming part of Letters Patent No. 423,514, dated March 18, 1890.

Application filed July 22, 1889. Serial No. 318,284. (No model.)

To all whom it may concern:

Be it known that I, FRANCIS EDWIN COFFEEN, a citizen of the United States, residing at Kanopolis, in the county of Ellsworth and State of Kansas, have invented a new and useful Tightener for Fences, of which the following is a specification.

This invention has relation to tighteners for barbed and other wire fences, and among 10 the objects in view are to provide an exceedingly cheap and efficient device adapted to grip and insert over the wire a suitable spindle and to be revolved, thereby winding said wire upon the spindle.

15 With these general objects in view the invention consists in a device having a pair of jaws the meeting faces of which are of a form adapted to receive the spindle, means for binding the jaws upon the spindle, and a 20 handle for revolving the twister.

Referring to the drawings, Figure 1 is a general view of a twister constructed in accordance with my invention, the same being in the act of tightening a barbed wire fence. 25 Fig. 2 is a plan of the twister in detail, the two jaws being separated and the binding device withdrawn therefrom. Fig. 3 is a detail of a section of fence-wire after having been operated upon by my twister.

30 Like numerals of reference indicate like parts in all the figures of the drawings.

In practicing my invention I form the main portion of the twister 1 in two sections 2 and 3. The section 2 consists of an enlarged head 35 portion 4, terminating in a rearwardly-disposed shank 5, having an opening 6, through which is passed the bolt 7 of an operating-handle 8. The opposite section, which I shall term the "clamping-section" 3, is a counter- 40 part of the section 2, with the exception of the rearwardly-disposed shank. The sections 2 and 3 are provided with perforations 9, through which is passed a binding-bolt 10, and upon the threaded end of the same and 45 binding upon the outer face of the section 3 is a binding-screw 10*. Each of the jaws of the two sections near its front end and upon its inner face is provided with a recess 11, semicircular in cross-section, which recesses, 50 when registering with each other, form a U-

shaped opening adapted to receive an ordinary staple, as 12. (See Fig. 3.) Around the recess 11 in each of the jaws there is formed a U-shaped groove 13, which by its peculiar location and construction is adapted to receive a second staple 19, similar to the first, with the exception that it is considerably longer and has its terminals oppositely bent.

The manner of using my device is as follows: A short and a long staple, as described, 60 are inserted in reverse directions in the recesses in the jaws. The ends of the staple 12 are placed across the strands of wire to be twisted. The thumb-nut is now tightened upon the screw and the clamping-jaw bound 65 tightly upon its companion, in so doing compressing the staple that is set edgewise into the jaws. It will be noticed that when in this clamped position the rear end of the clamping-jaw fits snugly against a square shoulder 70 15, formed by making the jaw of the section 2 less in thickness than with the shank portion of said section. The twister is now revolved laterally and as much wire taken up as necessary, after which the long terminals of one of 75 the staples are bent in reverse directions, as at 16, Fig. 4, and the strand of wire is prevented from untwisting.

It is apparent that numerous forms of staples may be substituted for those herein 80 shown, and that after one operation the bent terminals may be unbent and more slack taken up, if necessary.

An advantage accruing from the employment of staples as spindles is that a series of 85 staples projecting from a strand of wire may serve as a support for strips of wood—such as, for instance, laths, whereby cattle are prevented from running against the fence.

Having described my invention, what I 90 claim is—

1. In a wire-tightener, the main section formed with a transverse shoulder, in front of said shoulder being extended to form a clamping-jaw and in rear of the shoulder to 95 form a shank, in combination with a removable clamping-jaw mounted on the first-mentioned jaw and having its rear square end abutting against the shoulder when in a locked position, perforations formed in the 100

jaws, and a binding-bolt having a binding-nut mounted in the perforation, substantially as specified.

2. In a wire-tightener, a pair of independent separable jaws, each of which is provided with one-half of oppositely-disposed **U**-shaped staple-receiving recesses, substantially as specified.

3. In a wire-tightener, a pair of jaws held together by clamping devices and each pro-

vided with a **U**-shaped groove having a deep groove 11 between its branches, substantially as specified.

In testimony that I claim the foregoing as my own I have hereto affixed my signature 15 in presence of two witnesses.

FRANCIS EDWIN COFFEEN.
